(57) **CLAIM**

The ornamental design for a rotary valve, as shown and described.

DESCRIPTION

FIG. 1 is a perspective view of a rotary valve when seen from the top and right side of the front, showing the design; FIG. 2 is an elevational view thereof; FIG. 3 is a back view thereof; FIG. 4 is a left side view thereof; FIG. 5 is a right side view thereof; FIG. 6 is a top plan view thereof; FIG. 7 is a bottom plan view thereof; FIG. 8 is a cross section taken across FIG. 6 along line 8-8; FIG. 9 is a cross section taken across FIG. 6 along line 9-9; and, FIG. 10 is a cross section taken across FIG. 2 along line 10-10. The broken lines shown in the figures are included for the purpose of illustrating environment and form no part of the claimed design.
